Application March 16, 1944, Serial No. 526,794

5 Claims. (Cl. 158—36.4)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to fuel systems, and is particularly applicable to systems employing a plurality of fuel tanks, such, for instance, as the fuel system on an aircraft.

An object of the invention is to provide a fuel system of this character with means to maintain the pressure in the fuel line at its entrance to the carburetor or other fuel metering device substantially constant, while changing the connection which extends from the suction side of the main fuel pump from one tank to the next, as successive tanks are emptied.

More specifically, an object of the invention is to provide an emergency pump which becomes operative upon failure of the main pump to maintain the desired discharge pressure, and remains operative until the main pump has resumed substantially full discharge capacity.

Another object is to provide means to indicate when a shift from one main tank to the next should be made.

Other objects and advantages will become evident from a consideration of the following description, taken in conjunction with the drawings, wherein,

The single figure of the drawing is a schematic assembly view of the various elements of a fuel system arranged and connected according to the principles of our invention.

Like reference characters refer to like parts throughout the drawing.

Referring now to the drawing, an engine 10 carries a main fuel pump 12 which is operatively connected to the engine to be rotated thereby, and adapted to maintain a given constant fuel pressure at the fuel inlet 13 of the carburetor 14. A gauge 15 and a signal light 17 are provided for indicating when the fuel is being maintained at the desired pressure. A suction line 16 extends through a strainer 18 to the common outlet of the tank selector cock 20, the several inlets to the tank selector cock being respectively connected by supply pipes 22, 24 and 26 to the tanks 28, 30 and 32. The supply pipes 22 and 24 stop at the bottoms of their respective tanks 28 and 30, but the supply pipe 26 is prolonged so as to extend upwardly into the tank 32 as at 34, so that a reserve quantity of fuel 36 remains in the tank after the pipe 26 has drawn off fuel to the level of the upper end of the part 34. A short discharge line

2

37 connects the discharge side of the pump 12 to the carburetor fuel inlet 13.

An emergency fuel pump 38 is driven by an electric motor 40, which receives its operating current from a battery 42 or other appropriate source. A manual switch 43 is provided for disconnecting the battery from the electric circuits. A pressure responsive switch 44 completes electrical connection between the battery 42 and the motor 40 and signal light 17 whenever the pressure at the carburetor fuel inlet 13 falls several pounds below the predetermined pressure which the pumps 12 and 38 are set to maintain. Conduit means 46 connects the carburetor fuel inlet 13 to the pressure operated part of the switch 44. A discharge line 48 connects the discharge side of the emergency pump 38 into the short conduit 37 at the discharge side of the engine pump. A suction line 50 extends through a manually operable reserve connector cock 52 into the bottom of the tank 32, whereby the suction side of the emergency pump 38 is connected to the reserve fuel supply 36.

An air eliminator line 54 extends from the carburetor to the bottom of an air eliminator tank 56, which is partially filled with a liquid. A valve 58 in the line 54 permits it to be shut off when that becomes desirable. Since both pumps 12 and 38 have inbuilt relief valves which allow the fuel to move backwardly through the pumps when the fuel pressure at the discharge side exceeds a predetermined value, it may happen that when one pump is for any reason incapacitated, the good pump may force fuel backwardly through the damaged one, and for that reason, check valves 62 and 60 are provided, both biased to prevent backward flow in the lines 16 and 48, respectively. The pressure responsive part of the automatic switch 44 may preferably be so made that the switch, in shutting off the motor 40, will respond to a pressure several pounds lower than that at which the relief valve of the pump 12 is set.

The operation of the fuel system shown and described is substantially as follows:

Assume that the engine 10 is stopped, the pressure at the carburetor inlet 13 has dropped, and the tank selector cock 20 is turned to the position which connects the tank 28, through the supply pipe 22 and suction line 16 to the suction side of the engine pump 12. If the manual switch 43 is now closed, the emergency pump 38 will prime the carburetor, the switch 44 shutting off the motor when the pressure is up. If the engine is not immediately started, the emergency pump

may cycle, that is, pump up the desired pressure, stop, then let the pressure drop from leakage, then pump again. If, however, the engine is started at once, the engine pump 12 will pick up its prime, operate the switch 44 and thus stop the emergency pump 38. As long as the pump 12 is operating satisfactorily, the desired pressure will be maintained at the fuel inlet 13 of the carburetor. The check valve 62 will prevent fuel in the discharge line 48 from flowing backwardly through the pump 38 into the tank 32.

When the tank 28 becomes empty, it will be a matter of several seconds only until the engine pump 12 will be drawing some air through the suction line 16 and discharging it into the short conduit 37. When this occurs, the pressure at the fuel inlet 13 will drop almost instantly, and the automatic switch 44 will be actuated thereby to connect the battery 42 to the motor 40 of the emergency pump 38, whereupon the emergency pump 38 will maintain the desired fuel pressure at the carburetor fuel inlet 13, the air which had gotten into the short conduit 37 and into the carburetor, being discharged through the air eliminator line 54. It is noted that the discharge line 48 of the motor driven pump 38 is always full of fuel so that it needs only to be put under pressure to enable the pump 38 to take over when the pump 12 fails.

The pump 38 is, of course, designed for greater capacity than engine consumption, and may therefore cycle from this cause at intervals of several seconds. Thus the pressure at the fuel intake 13 will reach the desired value and the automatic switch 44 will stop the motor 40; then, as fuel is consumed, the pressure will drop at the inlet 13 a matter of several pounds, whereupon the switch 44 will again start the motor 40 to operate the pump 38.

This cycling may be observed on the pressure gauge 15, and by the flashing of the signal light 17, whereupon the tank selector cock 20 should be turned to connect the tank 30 or any other full tank to the suction side of the engine pump 12. Ordinarily, in less than half a minute, the pump 12 picks up the prime and raises the pressure at the fuel inlet 13 high enough to shut off the switch 44 and thus stop the motor pump 38.

If the system shown is being used in combat aircraft, it may happen that the tank 32 is punctured and the reserve supply 36 lost, or the engine pump 12 may be jammed or otherwise incapacitated. In such a case, the reserve connector cock 52 may be turned so as to connect the motor driven pump 38, through the tank selector cock 20, to any tank which may still contain fuel.

Having shown and described a physical embodiment of our invention, we claim:

1. The combination in an aircraft fuel system, of a main fuel supply receptacle, a main fuel pump having its suction side connected to said main fuel supply receptacle, a discharge-pressure control means for said main fuel pump, a reserve fuel supply container, an auxiliary fuel pump having its suction side connected to said reserve fuel supply container, a discharge-pressure control means for said auxiliary fuel pump, a fuel receiving means, the discharge side of both said pumps being connected to said fuel receiving means, the discharge-pressure control means of the auxiliary fuel pump being operable at the same pressure as the main fuel pump for delivering fuel to said fuel receiving means, and a pressure responsive means associated with the main fuel pump, adapted upon a predetermined drop

in pressure at the discharge side of the main fuel pump to operate said auxiliary fuel pump.

2. The combination, in an aircraft fuel system, of a plurality of main fuel supply receptacles, a main fuel pump, a discharge-pressure control means for connecting the suction side of said main fuel pump to any of said receptacles one at a time, a reserve fuel supply container, an electric motor driven auxiliary fuel pump, a discharge-pressure control means for said auxiliary fuel pump, means for connecting the suction side of said auxiliary fuel pump to said container, a fuel receiving means, means connecting the discharge side of both said pumps to said fuel receiving means, the discharge-pressure control means of the auxiliary fuel pump being operable at the same pressure as the main fuel pump for delivering fuel to said fuel receiving means, and an automatic electric switch responsive to a predetermined drop in pressure at the fuel inlet opening of said fuel receiving means to close and direct an electric current to operate said electric motor driven auxiliary fuel pump.

3. The combination, in an aircraft fuel system, of a plurality of main fuel supply receptacles, a main fuel pump, means for selectively connecting the suction side of said pump to any of said supply receptacles one at a time, a reserve fuel supply container, an auxiliary fuel pump, means connecting the suction side of said auxiliary fuel pump to said reserve fuel supply container, a fuel metering means, the discharge side of both said pumps being connected to said fuel metering means, valve means for disconnecting the suction side of the auxiliary fuel pump from said reserve fuel supply container and connecting it into the suction line of the main fuel pump, and a pressure responsive means associated with the fuel metering means, adapted, upon a predetermined drop in pressure at the fuel intake of said fuel metering means, to operate said auxiliary fuel pump.

4. The combination, in an aircraft fuel system, of a plurality of main fuel supply receptacles, a main fuel pump, a selector valve for connecting the suction inlet of said main fuel pump to said main fuel supply receptacles one at a time, a reserve fuel supply container, an auxiliary fuel pump, a reserve connector cock, a first, a second and a third port in said connector cock, a first passageway connecting the first port to the reserve fuel supply container, a second passageway connecting the second port to the suction side of the auxiliary pump, a third passageway connecting the third port into the suction line of the main fuel pump, means in said reserve connector cock operable to one position to connect the first port to the second, and to a second position to connect the second port to the third, a check valve in the suction line of said main fuel pump between said main fuel pump and the point of connection of the third said passageway with the main pump suction line, a carburetor, the discharge sides of both said pumps being connected to the fuel inlet of said carburetor, and an automatic means responsive to pressure drop at the fuel inlet of the carburetor to operate said auxiliary fuel pump.

5. The combination, in an aircraft fuel system, of a plurality of main fuel supply tanks, a main fuel pump, conduit means including a tank selector cock for selectively connecting the suction inlet of the main fuel pump to the several tanks one at a time, a check valve in said conduit means between said selector cock and said main fuel pump, biased to prevent fuel flow from said pump

back through said cock, a reserve fuel supply container, an emergency fuel pump, conduit means including a two way cock for selectively connecting the suction inlet of the emergency fuel pump either to the reserve fuel supply container or to the said main fuel pump conduit means at a point between said check valve and said tank selector cock, a carburetor, a conduit connecting the discharge sides of both pumps to the fuel inlet of said carburetor, a check valve in said conduit biased to prevent flow from the discharge side of the main fuel pump back through said emergency fuel pump, and an automatic means responsive to a pressure drop at the fuel inlet of the carburetor to operate said auxiliary fuel pump.
